ELECTROLESS PLATING SYSTEMS AND METHODS

FIELD

The present disclosure generally relates to electroless plating systems and methods for electroless plating.

BACKGROUND

Conventional electroless plating processes face significant challenges, particularly with premature plating. This issue occurs when the plating reactions initiate before the plating chemicals are even introduced to a plating vessel, leading to unwanted deposition of metal on surfaces and components outside the intended plating area. This not only wastes valuable materials but also contaminates equipment and complicates the plating process. This results in substantial downtime for maintenance to remove and clean the built-up plating on upstream components. These cleaning and maintenance processes are labor-intensive and time-consuming, reducing overall efficiency and increasing operational costs. Addressing these issues is desired for improving the reliability and efficiency of electroless plating systems.

Conventional electroless plating systems pose additional challenges stemming from an uneven chemical concentration in the electroless plating solution. This uneven concentration gradient, with a higher concentration in the upper bath region and a lower concentration in the lower bath region, causes thicker plating at the top and thinner plating at the bottom of the intended plating surface. Furthermore, the higher concentration of chemicals, particularly the reducing agent, in the upper bath region may cause the chemistry of the system to crash. Thus, maintaining an even concentration throughout the entire electroless plating solution is desired.

SUMMARY

Disclosed are electroless plating systems.

In one example, a disclosed electroless plating system includes a vessel defining an internal volume filled with an electroless plating solution wherein the electroless plating solution includes, but not limited to a solvent, a metal salt, and a reducing agent. The disclosed electroless plating system further includes a recirculation subsystem and a replenishment subsystem wherein the replenishment subsystem may include a replenishment inlet portion at a non-zero angle that introduces a variety of replenishment chemicals including, but not limited to the metal salt and the reducing agent.

Also disclosed are methods for electroless plating.

In one example, a disclosed method for electroless plating includes: immersing an article in an electroless plating solution; recirculating the electroless plating solution by drawing a portion of the electroless plating solution from an upper bath region and directing the portion of the electroless plating solution to a lower bath region; and replenishing the electroless plating solution by introducing a metal salt, a reducing agent, and an inert gas into an initial replenishment conduit segment of a replenishment conduit network to yield a replenishment mixture, wherein the initial replenishment conduit segment is disposed at a non-zero angle relative to a plane that is coincident with the bath surface.

Other examples of the disclosed electroless plating systems and methods for electroless plating will become apparent from the following detailed description, the accompanying drawings, and the appended claims.

DETAILED DESCRIPTION

Referring to FIG. 1, one example of the disclosed electroless plating system, generally designated 1000, includes a vessel 1050 defining an internal volume 1700. The vessel 1050 may take many different forms including, but not limited to cubical, cylindrical, and cuboid.

Turning to FIGS. 3 and 4, when selecting materials for the vessels 1050 and other internal components that make contacts with the electroless plating solution 1174, several factors must be considered to ensure optimal performance and durability. The materials for the electroless plating system 1000 including the vessel 1050 may be resistant to heated nature and chemicals used during electroless plating including, but not limited to acids for cleaning and maintenance, metal salts 1133, and reducing agents 1123. Those skilled in the art may choose an appropriate material depending on a given project. The appropriate material may include, but not limited to stainless steel, aluminum, aluminum alloy, titanium, polymers, and composite materials.

Referring to FIG. 4, an electroless plating solution 1174 received in the internal volume 1700 may define a bath surface 1173, an upper bath region 1103, a lower bath region 1101, and a middle bath region 1102 between the upper bath region 1103 and the lower bath region 1101. A height H of the electroless plating solution 1174 may vary depending on the size and shape of the vessel 1050.

45

50

55

60

In one example, the height H may be at least 30 cm. In another example, the height H may be at least 40 cm. In another example, the height H may be at least 50 cm. In another example, the height H may be at least 60 cm. In another example, the height H may be at least 70 cm. In another example, the height H may be at least 80 cm. In another example, the height H may be at least 90 cm. In another example, the height H may be at least 100 cm. In another example, the height H may be at least 120 cm. In another example, the height H may be at least 140 cm. In another example, the height H may be at least 160 cm. In another example, the height H may be at least 180 cm. In another example, the height H may be at least 2 meters. In another example, the height H may be at least 3 meters. In another example, the height H may be at least 3.5 meters. In another example, the height H may be at least 4 meters. In another example, the height H may be at least 5 meters. In another example, the height H may be at least 7.5 meters. In another example, the height H may be at least 10 meters. In another example, the height H may be at least 20 meters. In another example, the height H may be at least 30 meters.

Depending on the article **1104** that needs to be plated, the size of the vessel **1050** may vary. In one example, the article **1104** may be as small as a nut and bolt, in which case the internal volume **1700** of the vessel **1050** may only need to be equally small. In another example, the article **1104** may be a large portion of a wing of an air-plane, in which case the internal volume **1700** of the vessel **1050** may need to be very large.

In one example, the internal volume **1700** may be at least 1 liter. In another example, the internal volume **1700** may be at least 5 liters. In another example, the internal volume **1700** may be at least 10 liters. In another example, the internal volume **1700** may be at least 50 liters. In another example, the internal volume **1700** may be at least 100 liters. In another example, the internal volume **1700** may be at least 150 liters. In another example, the internal volume **1700** may be at least 200 liters. In another example, the internal volume **1700** may be at least 300 liters. In another example, the internal volume **1700** may be at least 400 liters. In another example, the internal volume **1700** may be at least 500 liters. In another example, the internal volume **1700** may be at least 700 liters. In another example, the internal volume **1700** may be at least 1000 liters.

Referring to FIGS. 8A, 8B and 9A, conventional electroless plating systems may pose challenges stemming from an uneven concentration gradient **8100** of the electroless plating solution **1174**. This uneven concentration gradient **8100**, with a higher concentration at an upper bath region **1103** and a lower concentration at a lower bath region **1101**, causes an uneven plating **9100** with thicker plating **9110**, **9210** at the top and a thinner plating **9120**, **9220** at the bottom of intended plating surfaces **9051**, **9052**. Furthermore, the higher concentration of chemicals, particularly the reducing agent **1123**, at the upper bath region **1103** may cause the tank chemistry to crash. Thus, it is desired to maintain a relatively even concentration **8200** throughout the entire electroless plating solution **1174**.

Turning to FIG. 7, this uneven concentration gradient **8100** challenge may be overcome by recirculating **6200** the electroless plating solution **1174**. The effectiveness of the recirculating **6200** the electroless plating solution **1174** may vary depending on the location of a recirculation inlet portion **1641** (FIGS. 1 and 2A) and the location of a recirculation outlet portion **1640** (FIG. 2A). In one example, the recirculation inlet portion **1641** may be disposed within the upper bath region **1103**. In another example, the recirculation outlet portion **1640** may be disposed within the lower bath region **1101**. In another example, the recirculation inlet portion **1641** may be disposed within the middle bath region **1102**. In another example, the recirculation outlet portion **1640** may be disposed within the upper bath region **1103**. In another example, the recirculation outlet portion **1640** may be disposed within the middle bath region **1102**. In another example, the recirculation outlet portion **1640** may be disposed within the lower bath region **1101**.

culation inlet portion **1641** may be disposed within a middle bath region **1102**. In another example, the recirculation outlet portion **1640** may be disposed within the middle bath region **1102**. In another example, the recirculation outlet portion **1640** may be disposed within the lower bath region **1101**.

In another example, a portion of the electroless plating solution **1174** from the upper bath region **1103** may be directed to lower bath region **1101**. In another example, a portion of the electroless plating solution **1174** from the upper bath region **1103** may be directed to the middle bath region **1102**. In another example, a portion of the electroless plating solution **1174** from the middle bath region **1102** may be directed to the lower bath region **1101**.

The area that each region **1101**, **1102**, **1103** covers may vary depending on a given project. Those skilled in the art may choose the coverage range. In one example, the upper bath region **1103** extends from about 60 percent of the height H to about 100 percent of the height H. In another example, the upper bath region **1103** extends from about 70 percent of the height H to about 100 percent of the height H. In another example, the upper bath region **1103** extends from about 80 percent of the height H to about 100 percent of the height H.

In another example, the lower bath region **1101** extends from about 0 percent of the height H to about 40 percent of the height H. In another example, the lower bath region **1101** extends from about 0 percent of the height H to about 30 percent of the height H. In another example, the lower bath region **1101** extends from about 0 percent of the height H to about 20 percent of the height H.

Referring again to FIG. 4, the electroless plating solution **1174** may be an aqueous mixture of chemicals including, but not limited to a solvent **1114**, a metal salt **1133**, and a reducing agent **1123**. In one example, the solvent **1114** may be water. In another example, the metal salt **1133** may be at least one of nickel sulfate and nickel chloride. In another example, the reducing agent **1123** may be sodium hypophosphite.

Referring to FIGS. 1 and 2, one example of the disclosed electroless plating system **1000** may further include a recirculation subsystem **1020** (FIG. 2A) and a replenishment subsystem **1010** (FIG. 2B). These subsystems **1020**, **1010** may be the key in solving issues that current conventional electroless plating systems present. In one example, the recirculation subsystem **1020** may help resolving the uneven concentration gradient **8100** issue of the electroless plating solution **1174**. In another example, the replenishment subsystem **1010** may help both the uneven concentration gradient **8100** issue of the electroless plating solution **1174** and the premature plating issue by introducing precise amount of each relevant chemicals separately at a predetermined time.

In one particular construction as shown in FIG. 1, a recirculation subsystem **1020** may include, but not limited to a pump **1300** and a recirculation conduit network **1021** at least partially immersed in the electroless plating solution **1174**. The recirculation conduit network **1021** may include a recirculation inlet portion **1641** in fluid communication with a recirculation outlet portion **1640** (FIG. 2A), wherein the recirculation inlet portion **1641** may be disposed within at least one of the upper bath region **1103** and the middle bath region **1102**, wherein the recirculation outlet portion **1640** may be disposed within at least one of the middle bath region **1102** and the lower bath region **1101**, and wherein the pump **1300** may be positioned to move the electroless plating solution **1174** from the recirculation inlet portion **1641** to the recirculation outlet portion **1640**. The overall

configuration of the recirculation conduit network 1021 may vary depending on a given project.

In one example as shown in FIG. 2A, the recirculation conduit network 1021 of the recirculation subsystem 1020 may further include, but not limited to an initial recirculation conduit segment 1200, a first horizontal recirculation portion 1202, a second vertical recirculation portion 1203A, and a third vertical recirculation portion 1203B. After entering the recirculation conduit network 1021 through the recirculation inlet portion 1641, a portion of the electroless plating solution 1174 from the upper bath region 1103 may go through the initial recirculation conduit segment 1200 that defines the recirculation inlet portion 1641.

In another example, the initial recirculation conduit segment 1200 of the recirculation conduit network 1021 may be vertically immersed in the electroless plating solution 1174, as shown in FIG. 1. In another example, the initial recirculation conduit segment 1200 of the recirculation conduit network 1021 may guide the portion of the electroless plating solution 1174 from the upper bath region 1103 upward out of the electroless plating solution 1174, over a wall 1051, and downward to the lower bath region. In other words, as long as the recirculation subsystem 1020 directs the portion of the electroless plating solution 1174 from the upper bath region 1103 to the lower bath region, the purpose of the recirculation subsystem 1020 may be satisfied. Thus, a proper configuration of the recirculation conduit network 1021 of the recirculation subsystem 1020 is desired.

Referring again to FIG. 2A, the second vertical recirculation portion 1203A may be fluidly coupled with the initial recirculation conduit segment 1200 through the first horizontal recirculation portion 1202 and may be configured to move the portion of the electroless plating solution 1174 from the upper bath region 1103 vertically upward over a wall 1051 of a vessel 1050. The third vertical recirculation portion 1203B that is fluidly coupled with the second vertical recirculation portion 1203A and the recirculation outlet portion 1640 may be configured to move the portion of electroless plating solution 1174 from the upper bath region 1103 vertically downward to the lower bath region 1101.

Once the portion of the electroless plating solution 1174 from the upper bath region 1103 reaches the lower bath region 1101, it may be released into the electroless plating solution 1174 in the vessel 1050 through a recirculation outlet portion 1640. However, for more even distribution and efficiency, an initial recirculation flow 1207 of the electroless plating solution 1174 from the upper bath region 1103 may be divided into a plurality of divided recirculation flows 1208A, 1208B (FIG. 5A). As shown in FIGS. 2A and 5A, the recirculation conduit network 1021 may further include a recirculation diverging junction 1204 that divides an initial recirculation flow 1207 from the third vertical recirculation portion 1203B into at least two divided recirculation flows 1208A, 1208B. In the current example, the initial recirculation flow 1207 may be divided into two divided recirculation flows 1208A, 1208B.

Referring again to FIG. 2A, for more even distribution, the recirculation conduit network 1021 may further include a second horizontal recirculation portion 1205 that is fluidly coupled with the third vertical recirculation portion 1203B at the recirculation diverging junction 1204 and defines a plurality of recirculation outlet portions 1640. The divided recirculation flows 1208A, 1208B may travel through the second horizontal portion 1205 and may be released into the electroless plating solution 1174 in the vessel 1050 at

different parts of the lower bath region 1101 where the plurality of recirculation outlet portions 1640 are disposed.

Generally, an electroless plating system 1000 depletes certain chemicals including, but not limited to a metal salt 1133 and a reducing agent 1123 within an electroless plating solution 1174 in a vessel 1050 while the electroless plating system 1000 is running. In other words, those used chemicals during the process may need to be replenished to maintain the overall chemical balance of the electroless plating solution 1174 in the vessel 1050 of the electroless plating system 1000. Because the reducing agent 1123 is the main trigger of the electroless plating process, to reduce premature plating, it is desired to minimize the time between mixing the reducing agent 1123 with other chemicals, creating a replenishment mixture 1160, and introducing that replenishment mixture 1160 into the electroless plating solution 1174 in the vessel 1050.

In one particular construction as shown in FIGS. 1, 2B, and 3, a replenishment subsystem 1010 may include a replenishment conduit network 1011, a bulk supply 1132 of the metal salt 1133, a bulk supply 1122 of the reducing agent 1123, and a bulk supply 1112 of an inert gas 1113. The replenishment conduit network 1011 may include a replenishment inlet portion 1631 that is in fluid communication with a replenishment outlet portion 1630 disposed within at least one of the middle bath region 1102 and the lower bath region 1101. The replenishment conduit network 1011 may further include an initial replenishment conduit segment 1100 that defines the replenishment inlet portion 1631 disposed at a non-zero angle 1170 relative to a plane P that is coincident with a bath surface 1173 of the electroless plating solution 1174, wherein the bulk supply 1132 of the metal salt 1133, the bulk supply 1122 of the reducing agent 1123, and the bulk supply 1112 of the inert gas 1113 are in selective fluid communication with the replenishment inlet portion 1631 of the replenishment conduit network 1011.

Still referring to the particular construction above, the replenishment conduit network 1011 of the replenishment subsystem 1010 may further include a first horizontal replenishment portion 1501 that is fluidly coupled with the initial replenishment conduit segment 1100 and a vertical replenishment portion 1502, wherein the vertical replenishment portion 1502 that is fluidly coupled with the initial replenishment conduit segment 1100, the vertical replenishment portion 1502 being configured to move a replenishment mixture 1160 vertically downward to the lower bath region 1101, and the vertical replenishment portion 1502 that is in fluid communication with the replenishment outlet portion 1630.

Once the replenishment mixture 1160 reaches the lower bath region 1101, it may be released into the electroless plating solution 1174 in the vessel 1050. Referring to FIGS. 1, 2B and 5B, to facilitate more even distribution of the replenishment mixture 1160, the replenishment conduit network 1011 of the replenishment subsystem 1010 may further include a replenishment diverging junction 1504 at the end of the vertical replenishment portion 1502. An initial replenishment flow 1507 from the vertical replenishment portion 1502 may be divided into at least two divided replenishment flows 1508A, 1508B at the replenishment diverging junction 1504. These divided replenishment flows 1508A, 1508B may travel through a second horizontal replenishment portion 1505 that is fluidly coupled with the vertical replenishment portion 1502 at the replenishment diverging junction 1504 and defines the replenishment outlet portion 1630.

Those skilled in the art may need to choose the value of the non-zero angle 1170 carefully because it provides gravi-

tational force and ensures sequential injection of different chemicals into the replenishment subsystem **1010**. In one example, the non-zero angle **1170** may be between about 5 degrees and about 90 degrees. In another example, the non-zero angle **1170** may be between about 5 degrees and about 70 degrees. In another example, the non-zero angle **1170** may be between about 10 degrees and about 60 degrees. In another example, the non-zero angle **1170** may be between about 10 degrees and about 50 degrees. In another example, the non-zero angle **1170** may be between about 15 degrees and about 45 degrees. In another example, the non-zero angle **1170** may be between about 20 degrees and about 40 degrees.

In another example, the non-zero angle **1170** may be at least 10 degrees. In another example, the non-zero angle **1170** may be at least 15 degrees. In another example, the non-zero angle **1170** may be at least 20 degrees. In another example, the non-zero angle **1170** may be at least 25 degrees. In another example, the non-zero angle **1170** may be at least 30 degrees. In another example, the non-zero angle **1170** may be at least 35 degrees. In another example, the non-zero angle **1170** may be at least 40 degrees. In another example, the non-zero angle **1170** may be at least 45 degrees. In another example, the non-zero angle **1170** may be at least 50 degrees. In another example, the non-zero angle **1170** may be at least 60 degrees. In another example, the non-zero angle **1170** may be at least 70 degrees. In another example, the non-zero angle **1170** may be at least 80 degrees. In another example, the non-zero angle **1170** may be about 90 degrees.

The electroless plating solution **1174** may involve more than one metal salt **1133** for a given project and this may require introducing more than one replenishment metal salts **1133, 1143, 1153**. In one example, there may be at least one bulk supply **1132** of the metal salt **1133**. In another example, there may be at least two bulk supplies **1132, 1142** of metal salts **1133, 1143**. In another example, there may be at least three bulk supplies **1132, 1142, 1152** of metal salts **1133, 1143, 1153**.

The electroless plating system **1000** is very sensitive and just a slight change in its chemical balance may result in total collapse of the system. This is why it is very desired to replenish just the right amount of chemicals at the replenishment inlet portion **1631**. In one example, the right amount of any replenishment chemical may be released by a displacement pump. As shown in FIG. 3, replenishment chemical flows **1120, 1130, 1140, 1150** may be precisely controlled and released by displacement pumps **1121, 1131, 1141, 1151** disposed between the corresponding bulk supplies **1122, 1132, 1142, 1152** and the replenishment inlet portion **1631** of the replenishment conduit network **1011**. These displacement pumps **1121, 1131, 1141, 1151** provide selective fluid communication between bulk supplies **1122, 1132, 1142, 1152** and the replenishment inlet portion **1631** of the replenishment conduit network **1011**.

In one example, a first metal salt displacement pump **1131** is disposed in between the bulk supply **1132** of the metal salt **1133** and the replenishment inlet portion **1631** of the replenishment conduit network **1011** for a metered release. In another example, a second metal salt displacement pump **1141** is disposed in between the bulk supply **1142** of a second metal salt **1143** and the replenishment inlet portion **1631** of the replenishment conduit network **1011** for a metered release. In another example a third metal salt displacement pump **1151** is disposed in between the bulk supply **1152** of a third metal salt **1153** and the replenishment inlet portion **1631** of the replenishment conduit network

1011 for a metered release. In another example, a reducing agent displacement pump **1121** is disposed in between the bulk supply **1122** of the reducing agent **1123** and the replenishment inlet portion **1631** of the replenishment conduit network **1011** for a metered release.

As mentioned earlier, to reduce premature plating, it is desired to minimize the time between mixing the reducing agent **1123** with other chemicals including, but not limited to an inert gas **1113** and metal salts **1133, 1143, 1153**, creating a replenishment mixture **1160**, and introducing that replenishment mixture **1160** into the electroless plating solution **1174** in the vessel **1050**. One way of reducing this time is by making the replenishment mixture **1160** travel faster using a pressurized inert gas **1113** that includes, but not limited to nitrogen. The inert nature of the inert gas may reduce premature plating. A pressure regulator **1111** may be disposed between the bulk supply **1112** of the inert gas **1113** and the replenishment inlet portion **1631** of the replenishment conduit network **1011**.

As much as a proper configuration of the inlet portions **1631, 1641** of the subsystems **1010, 1020** is desired for maintaining the chemical balance of the electroless plating system **1000**, a proper configuration of the outlet portions **1630, 1640** of the subsystems **1010, 1020** is equally desired. Proper configurations of these outlet portions **1630, 1640** ensure efficient operation and help to prevent issues that could otherwise disrupt the chemical balance, contributing to the overall effectiveness and longevity of the electroless plating system **1000**.

Those skilled in the art may choose proper configurations of the outlet portions **1630, 1640** depending on the specifics of a given project. In one example, referring to FIGS. 5A, 5B, and 6, the recirculation outlet portion **1640** and the replenishment outlet portion **1630** may be placed separately at different locations. In other words, each of the divided recirculation flows **1208A, 1208B** and the divided replenishment flows **1508A, 1508B** are individually and separately introduced into the electroless plating solution **1174** in the vessel **1050**.

In another example, referring to FIGS. 5A, 5B, and 6, one of the divided recirculation flows **1208A, 1208B** and one of the divided replenishment flows **1508A, 1508B** may merge into a unified flow **1650** at an outlet merging junction **1620**. This unified flow **1650** may be released into the electroless plating solution **1174** in the vessel **1050**. For a better-distributed release, those skilled in the art may choose to use various release features **1690**, including but not limited to spargers **1600** with a plurality of sparger holes **1610**, wherein each sparger hole **1610** represents a point of release **1611**. The larger the spargers **1600** and the greater the number of sparger holes **1610**, the more effectively the release is distributed.

In one example, the release feature **1690** may have at least 1 point of release **1611**. In another example, the release feature **1690** may have at least 10 points of release **1611**. In another example, the release feature **1690** may have at least 30 points of release **1611**. In another example, the release feature **1690** may have at least 50 points of release **1611**. In another example, the release feature **1690** may have at least 100 points of release **1611**. In another example, the release feature **1690** may have at least 200 points of release **1611**. In another example, the release feature **1690** may have at least 300 points of release **1611**.

The electroless plating system **1000** may further include at least one heater **1800** (FIG. 1), as it may require an elevated temperature of the electroless plating solution **1174**. Those skilled in the art may choose the exact type and

location of the heater **1800**, as each project may require different specifications of the heater **1800**. In one example, the heater **1800** may be placed at the bottom of the vessel **1050**. In another example, the heater **1800** may be placed on the wall **1051** of the vessel **1050**. In another example, the heater **1800** may be placed within at least one of the subsystems **1010, 1020**.

In order to check the status of the chemical balance of the electroless plating solution **1174**, the electroless plating system **1000** may require at least one analyzer **1400** that measures various parameters of the electroless plating solution **1174** and replenishment **6300** chemicals. Those parameters may include, but not limited to concentration of the reducing agent **1123** and the metal salt **1133**, temperature, and pH level of the electroless plating solution **1174**. The information measured by the analyzer **1400** may be used to determine the amount and speed of replenishment **6300** and recirculation **6200**. Those skilled in the art may choose the location of the analyzer **1400** and how often they want to measure based on a given project. In one example, the analyzer **1400** may be placed at the bottom of the vessel **1050**. In another example, the analyzer **1400** may be placed on the wall **1051** of the vessel **1050**. In another example, the analyzer **1400** may be placed within at least one of the subsystems **1010, 1020**. In another example, there may be several more than one analyzer **1400** at different locations. In another example, there may be at least two analyzers **1400** along the depth of the electroless plating solution **1174** that can measure the concentration gradients **8100, 8200**.

For the interval of the measurement, the analyzer **1400** may continuously monitor the parameters of the electroless plating solution **1174**. In another example, the analyzer **1400** may measure the parameters of the electroless plating solution **1174** at specific intervals. In another example, the analyzer **1400** may measure the parameters of the electroless plating solution **1174** at an interval of at least 0.05 seconds. In another example, the analyzer **1400** may measure the parameters of the electroless plating solution **1174** at an interval of at least 0.1 seconds. In another example, the analyzer **1400** may measure the parameters of the electroless plating solution **1174** at an interval of at least 0.5 seconds. In another example, the analyzer **1400** may measure the parameters of the electroless plating solution **1174** at an interval of at least 1 second. In another example, the analyzer **1400** may measure the parameters of the electroless plating solution **1174** at an interval of at least 2 seconds. In another example, the analyzer **1400** may measure the parameters of the electroless plating solution **1174** at an interval of at least 3 seconds. In another example, the analyzer **1400** may measure the parameters of the electroless plating solution **1174** at an interval of at least 5 seconds. In another example, the analyzer **1400** may measure the parameters of the electroless plating solution **1174** at an interval of at least 0.05-10 seconds.

Referring to FIG. 10, the electroless plating system **1000** may further need a control unit **1900** that is in communication **1910** with all the relevant components including, but not limited to the analyzer **1400**, the heater **1800**, the recirculation pump **1300**, displacement pumps **1121, 1131, 1141, 1151**, and the pressure regulator **1111**. These communications **1910** may be in various formats, including but not limited to wired and wireless. Additionally, these communications **1910** between the control unit **1900** and the relevant components may be either one-way, where information is only transmitted in a single direction, or two-way, allowing for an interactive exchange of data. In one example, the information gathered by the analyzer **1400** may

be sent to the control unit, and the control unit may be programmed by those skilled in the art to send a command to one of the displacement pumps **1121, 1131, 1141, 1151** to make a controlled, metered release of a depleted chemical based on the information from the analyzer **1400**. In another example, the control unit **1900** may control the heater **1800** to increase or decrease the temperature of the electroless plating solution **1174**.

Referring now to FIG. 7, disclosed is an example of a method **6000** for electroless plating that utilizes a recirculation subsystem **1020** and a replenishment subsystem **1010**. The method **6000** includes, but not limited to: immersing **6100** an article **1104** in an electroless plating solution **1174**; recirculating **6200** the electroless plating solution **1174** by drawing a portion of the electroless plating solution **1174** from at least one of the upper bath region **1103** and the middle bath region **1102**, and directing the portion of the electroless plating solution **1174** to at least one of the middle bath region **1102** and the lower bath region **1101**; and replenishing **6300** the electroless plating solution **1174** by introducing depleted chemicals including but not limited to a metal salt **1133**, a reducing agent **1123**, and an inert gas **1113** into an initial replenishment conduit segment **1100** of a replenishment conduit network **1011** to yield a replenishment mixture **1160**, wherein the replenishment conduit network **1011** directs the replenishment mixture **1160** to at least one of the middle bath region **1102** and the lower bath region **1101**.

Immersing **6100** the article **1104** into the electroless plating solution **1174** requires careful attention to ensure optimal results. Before the immersing **6100** step, the article **1104** must be thoroughly cleaned and free of contaminants to allow for proper adhesion of the plating material. The article **1104** may be immersed using various ways including, but not limited to a support structure and a hanger that ensures full submersion. The immersing **6100** step may be conducted at a controlled and steady pace to avoid introducing air bubbles or causing agitation that might disturb the balance of the electroless plating solution **1174**. Those skilled in the art may choose an appropriate pace based on the specifics of a given project.

Proper positioning of the article **1104** within the electroless plating solution **1174** is desired to achieve a uniform plating **9200**. In one example, the article **1104** may be placed in the upper bath region **1103**. In another example, the article **1104** may be placed in the middle bath region **1102**. In another example, the article **1104** may be placed in the lower bath region **1101**. In another example, the article **1104** may be placed across different regions **1101, 1102, 1103**. Those skilled in the art may choose an appropriate position based on the specifics of a given project.

The electrolessly plating method **6000** is a highly sensitive and unstable chemical process that demands meticulous control and precision. Unlike traditional electroplating, which relies on an external electrical power source, electroless plating relies on a chemical reduction reaction to deposit a metal layer on a substrate. This reaction is highly susceptible to variations in chemical balances including, but not limited to metal salt concentrations and reducing agent concentrations, temperature, and PH levels. Even minor fluctuations can lead to an uneven plating **9100**, poor adhesion, and unexpected deposition rates. Thus, the electrolessly plating method **6000** requires constant monitoring and precise management of the chemical balance of the electroless plating solution to prevent issues including, but not limited to premature plating, solution instability, and chemistry crashes.

11

Referring to FIGS. 8A and 9A, an uneven concentration gradient **8100** of chemicals, including but not limited to metal salts **1133**, **1143**, **1153** and the reducing agent **1123** in the electroless plating solution **1174**, is likely to yield an uneven plating **9100**. Through the method **6000** that involves the recirculating **6200** step, it may be possible to achieve a relatively even concentration gradient **8200** as shown in FIG. 8B which in turn would yield a relatively more uniform plating **9200** as shown in FIG. 9B.

To minimize the uneven concentration gradient **8100**, the disclosed method **6000** may involve various steps of mixing the electroless plating solution **1174** including, but not limited to recirculating **6200** by taking a portion of the electroless plating solution **1174** from the upper bath region **1103** and introducing it back down to the lower bath region **1101**. In one example, by performing the recirculating **6200** step, the electroless plating solution **1174** with a higher concentration of reducing agent **1123** mixes with the electroless plating solution **1174** with a lower concentration of reducing agent **1123**. Those skilled in the art may choose the rate at which the recirculating **6200** is performed based on the specifics of a given project.

The method **6000** for electrolessly plating inherently results in the depletion of certain chemicals, including but not limited to metal salts **1133**, **1143**, **1153** and the reducing agent **1123**, within the electroless plating solution **1174** contained in a vessel **1050**. This depletion occurs continuously while the system is running. To maintain an overall chemical balance of the electroless plating solution **1174**, it is essential to replenish these consumed chemicals. The manner in which the replenishment **6300** chemicals, including but not limited to metal salts **1133**, **1143**, **1153** and the reducing agent **1123**, are introduced affects premature plating and thus plays a key role in determining the life cycle of the electroless plating system **1000**. Therefore, it is desired to find a proper method of replenishment that does not interrupt the electroless plating system **1000** while introducing just the right amount of replenishment mixtures **1160** at the right time and at the right rate.

In one example, the method **6000** may involve a replenishment **6300** step to replenish the consumed reducing agent **1123** and metal salts **1133**, **1143**, **1153**. Referring to FIGS. 1 and 3, each replenishment **6300** chemicals may be introduced through a replenishment inlet portion **1631** individually and sequentially as a replenishment reducing agent flow **1120** and replenishment metal salt flows **1130**, **1140**, **1150**. As illustrated in FIG. 3, a pressurized inert gas flow **1110** first merges with the replenishment reducing agent flow **1120**, forming a first replenishment mixture **1115**. In this example, the first replenishment mixture starts to travel through an initial replenishment conduit segment **1100** disposed at a non-zero angle **1170** relative to a plane P that is coincident with a bath surface **1173**. As the first replenishment mixture travels, at least one replenishment chemicals, including but not limited to the replenishment metal salt flows **1130**, **1140**, **1150**, may be injected sequentially one by one, eventually forming a replenishment mixture **1160**. After traveling through the replenishment conduit network **1011**, the replenishment mixture **1160** may be released into the electroless plating solution **1174** in the vessel **1050** through a replenishment outlet portion **1630**. This inert gas propelled replenishment **6300** may reduce the uneven concentration gradient **8100** and premature plating on unintended surfaces and components before getting introduced to the electroless plating solution **1174** in the vessel **1050**.

Those skilled in the art may choose to introduce the replenishment mixture **1160** at an appropriate value of the

12

non-zero angle **1170** depending on a given project. In one example, the non-zero angle **1170** may be between about 5 degrees and about 90 degrees. In another example, the non-zero angle **1170** may be between about 5 degrees and about 70 degrees. In another example, the non-zero angle **1170** may be between about 10 degrees and about 60 degrees. In another example, the non-zero angle **1170** may be between about 10 degrees and about 50 degrees. In another example, the non-zero angle **1170** may be between about 15 degrees and about 45 degrees. In another example, the non-zero angle **1170** may be between about 20 degrees and about 40 degrees.

In another example, the non-zero angle **1170** may be at least 10 degrees. In another example, the non-zero angle **1170** may be at least 15 degrees. In another example, the non-zero angle **1170** may be at least 20 degrees. In another example, the non-zero angle **1170** may be at least 25 degrees. In another example, the non-zero angle **1170** may be at least 30 degrees. In another example, the non-zero angle **1170** may be at least 35 degrees. In another example, the non-zero angle **1170** may be at least 40 degrees. In another example, the non-zero angle **1170** may be at least 45 degrees. In another example, the non-zero angle **1170** may be at least 50 degrees. In another example, the non-zero angle **1170** may be at least 60 degrees. In another example, the non-zero angle **1170** may be at least 70 degrees. In another example, the non-zero angle **1170** may be at least 80 degrees. In another example, the non-zero angle **1170** may be about 90 degrees.

As much as a proper configuration of the inlet portions **1631**, **1641** of the subsystems **1010**, **1020** is desired for maintaining the chemical balance of the electroless plating system **1000**, a proper configuration of the outlet portions **1630**, **1640** of the subsystems **1010**, **1020** is equally desired. Proper release through these outlet portions **1630**, **1640** ensure efficient operation and help to prevent issues that could otherwise disrupt the chemical balance, contributing to the overall effectiveness and longevity of the electroless plating system **1000**.

Those skilled in the art may choose a proper method of release through the outlet portions **1630**, **1640** depending on the specifics of a given project. In one example, recirculating **6200** flows and replenishment **6300** flows may be introduced to the electroless plating solution **1174** in the vessel **1050** separately at their own rate. In another example, recirculating **6200** flows and replenishment **6300** flows may be introduced to the electroless plating solution **1174** in the vessel **1050** together as a unified flow **1650** as shown in FIG. 6.

In another example, those skilled in the art may choose to use an additional release system including, but not limited to a sparger **1600** with a plurality of holes **1610**. Each hole **1610** acts as a point of release **1611**. Therefore, the greater the number of sparger holes **1610**, the more effectively the release is distributed. In one example, recirculating **6200** flows and replenishment **6300** flows may be introduced to the electroless plating solution **1174** in the vessel **1050** through at least 10 different points of release **1611**. In another example, recirculating **6200** flows and replenishment **6300** flows may be introduced to the electroless plating solution **1174** in the vessel **1050** through at least 30 different points of release **1611**. In another example, recirculating **6200** flows and replenishment **6300** flows may be introduced to the electroless plating solution **1174** in the vessel **1050** through at least 50 different points of release **1611**. In another example, recirculating **6200** flows and replenishment **6300** flows may be introduced to the electroless plating

13

solution 1174 in the vessel 1050 through at least 70 different points of release 1611. In another example, recirculating 6200 flows and replenishment 6300 flows may be introduced to the electroless plating solution 1174 in the vessel 1050 through at least 100 different points of release 1611. In another example, recirculating 6200 flows and replenishment 6300 flows may be introduced to the electroless plating solution 1174 in the vessel 1050 through at least 200 different points of release 1611. In another example, recirculating 6200 flows and replenishment 6300 flows may be introduced to the electroless plating solution 1174 in the vessel 1050 through at least 300 different points of release 1611.

Size and shape of the holes (1610) may vary depending on a given project. Those skilled in the art may choose a proper size and shape of the holes (1610). In one example, the holes (1610) may be circular with a diameter of at least 1 mm. In another example, the holes (1610) may be circular with a diameter of at least 5 mm. In another example, the holes (1610) may be circular with a diameter of at least 10 mm. In another example, the holes (1610) may be circular with a diameter of at least 15 mm. In another example, the holes (1610) may be circular with a diameter of at least 30 mm. In another example, the holes (1610) may be circular with a diameter of at least 50 mm. In another example, the holes (1610) may be circular with a diameter of at least 100 mm.

Even though the two subsystems 1010, 1020 operate independently, they are functionally interdependent as both affect the chemistry balance of the electroless plating system 1000. Therefore, those skilled in the art may need to determine when each subsystem 1010, 1020 operates. In one example, both subsystems 1010, 1020 may operate simultaneously. In another example, the recirculation subsystem 1020 may operate while the replenishment subsystem 1010 is off. In another example, the recirculation subsystem 1020 may be off while the replenishment subsystem 1010 is operating.

What is claimed is:

1. An electroless plating system comprising:
a vessel defining an internal volume;
an electroless plating solution received in the internal volume of the vessel such that the electroless plating solution defines a bath surface, an upper bath region comprising the bath surface, a lower bath region, and a middle bath region between the upper bath region and the lower bath region, the electroless plating solution comprising a solvent, a metal salt, and a reducing agent;
a recirculation subsystem comprising a pump and a recirculation conduit network at least partially immersed in the electroless plating solution, the recirculation conduit network comprising a recirculation inlet portion in fluid communication with a recirculation outlet portion, wherein the recirculation inlet portion is disposed within at least one of the upper bath region and the middle bath region, wherein the recirculation outlet portion is disposed within at least one of the middle bath region and the lower bath region, and wherein the pump is positioned to move the electroless plating solution from the recirculation inlet portion to the recirculation outlet portion; and
a replenishment subsystem comprising a replenishment conduit network, a bulk supply of the metal salt, a bulk supply of the reducing agent, and a bulk supply of an inert gas, the replenishment conduit network comprising a replenishment inlet portion in fluid communication with a replenishment outlet portion, the replenish-

14

ment outlet portion being disposed within at least one of the middle bath region and the lower bath region, the replenishment conduit network further comprising an initial replenishment conduit segment that defines the replenishment inlet portion, the initial replenishment conduit segment being disposed at a non-zero angle relative to a plane that is coincident with the bath surface of the electroless plating solution, wherein the bulk supply of the metal salt, the bulk supply of the reducing agent, and the bulk supply of the inert gas are in selective fluid communication with the replenishment inlet portion of the replenishment conduit network.

2. The electroless plating system of claim 1 wherein the electroless plating solution in the internal volume of the vessel has a height, and wherein the upper bath region extends from about 80 percent of the height to about 100 percent of the height.

3. The electroless plating system of claim 1 wherein the electroless plating solution in the internal volume of the vessel has a height, and wherein the lower bath region extends from about 0 percent of the height to about 20 percent of the height.

4. The electroless plating system of claim 1 wherein the recirculation conduit network comprises an initial recirculation conduit segment that is at least partially immersed in the electroless plating solution in a vertical orientation and defines the recirculation inlet portion.

5. The electroless plating system of claim 4 wherein the recirculation conduit network further comprises:

a second vertical recirculation portion that is fluidly coupled with the initial recirculation conduit segment, the second vertical recirculation portion being configured to move the electroless plating solution from the upper bath region vertically upward over a wall of the vessel; and

a third vertical recirculation portion that is fluidly coupled with the second vertical recirculation portion, the third vertical recirculation portion being configured to move the electroless plating solution from the upper bath region vertically downward to the lower bath region, the third vertical recirculation portion that is in fluid communication with the recirculation outlet portion.

6. The electroless plating system of claim 5 wherein the recirculation conduit network further comprises a recirculation diverging junction that divides an initial recirculation flow from the third vertical recirculation portion into two divided recirculation flows.

7. The electroless plating system of claim 6 wherein the recirculation conduit network further comprises a second horizontal recirculation portion that is fluidly coupled with the third vertical recirculation portion at the recirculation diverging junction and defines the recirculation outlet portion.

8. The electroless plating system of claim 7 wherein the second horizontal recirculation portion leads the divided recirculation flows to different parts of the lower bath region.

9. The electroless plating system of claim 1 the non-zero angle is between about 10 degrees and about 50 degrees.

10. The electroless plating system of claim 1 wherein a first metal salt displacement pump is disposed in between the bulk supply of the metal salt and the replenishment inlet portion of the replenishment conduit network for a metered release.

11. The electroless plating system of claim 1 wherein a reducing agent displacement pump is disposed in between

15

the bulk supply of the reducing agent and the replenishment inlet portion of the replenishment conduit network for a metered release.

12. The electroless plating system of claim **1** wherein a pressure regulator is disposed between the bulk supply of the inert gas and the replenishment inlet portion of the replenishment conduit network for a metered release. 5

13. The electroless plating system of claim **1** wherein the replenishment conduit network further comprises a vertical replenishment portion that is fluidly coupled with the initial replenishment conduit segment, the vertical replenishment portion being configured to move a replenishment mixture vertically downward to the lower bath region, and the vertical replenishment portion that is in fluid communication with the replenishment outlet portion. 10

14. The electroless plating system of claim **13** wherein the replenishment conduit network further comprises a replenishment diverging junction that divides an initial replenishment flow from the vertical replenishment portion into two divided replenishment flows. 15

15. The electroless plating system of claim **14** wherein the replenishment conduit network further comprises a second horizontal replenishment portion that is fluidly coupled with the vertical replenishment portion at the replenishment diverging junction and defines the replenishment outlet 20 portion. 25

16. The electroless plating system of claim **1** wherein the recirculation outlet portion merges with the replenishment outlet portion at an outlet merging junction.

17. The electroless plating system of claim **16** further comprising a sparger in fluid communication with the outlet merging junction. 30

18. The electroless plating system of claim **1** further comprising an analyzer positioned to measure at least one of a reducing agent concentration in the electroless plating solution, a pH level of the electroless plating solution, and a temperature of the electroless plating solution. 35

19. An electroless plating system comprising:
a vessel defining an internal volume;
an electroless plating solution received in the internal 40 volume of the vessel such that the electroless plating solution defines a bath surface, an upper bath region

16

comprising the bath surface, and a lower bath region below the upper bath region, the electroless plating solution comprising a solvent, a first metal salt, a second metal salt, and a reducing agent;

a recirculation subsystem comprising a pump and a recirculation conduit network at least partially immersed in the electroless plating solution, the recirculation conduit network comprising a recirculation inlet portion in fluid communication with a recirculation outlet portion, wherein the recirculation inlet portion is disposed within the upper bath region, wherein the recirculation outlet portion is disposed within the lower bath region, and wherein the pump is positioned to move the electroless plating solution from the recirculation inlet portion to the recirculation outlet portion; and

a replenishment subsystem comprising a replenishment conduit network, a bulk supply of the first metal salt, a bulk supply of the second metal salt, a bulk supply of the reducing agent, and a bulk supply of an inert gas, the replenishment conduit network comprising a replenishment inlet portion in fluid communication with a replenishment outlet portion, the replenishment outlet portion being disposed within the lower bath region, the replenishment conduit network further comprising an initial replenishment conduit segment that defines the replenishment inlet portion, the initial replenishment conduit segment being disposed at an angle of about 10 degrees to about 50 degrees relative to a plane that is coincident with the bath surface of the electroless plating solution, wherein the bulk supply of the first metal salt, the bulk supply of the second metal salt, the bulk supply of the reducing agent, and the bulk supply of the inert gas are in selective fluid communication with the replenishment inlet portion of the replenishment conduit network.

20. The electroless plating system of claim **1** wherein the electroless plating solution in the internal volume of the vessel has a height, and wherein the upper bath region extends from about 60 percent of the height to about 100 percent of the height.

* * * * *
